UNITED STATES PATENT OFFICE.

ALFRED R. MACKIE, OF LANDER, WYOMING.

CONCENTRATOR.

1,344,051.

Specification of Letters Patent. Patented June 22, 1920.

Application filed July 10, 1919. Serial No. 309,804.

To all whom it may concern:

Be it known that I, ALFRED R. MACKIE, a citizen of the United States, and a resident of Lander, in the county of Fremont and 5 State of Wyoming, have invented a new and Improved Concentrator, of which the following is a full, clear, and exact description.

This invention relates to improvements in 10 concentrators, and, more particularly, to a concentrator such as employed in the concentrating of placer gold and the like.

One of the objects of this invention is to 15 provide a concentrator having an improved construction and arrangement of traveling riffle or riffles, which can be set at different angles, relative to the concentrating surface, to control to a certain extent the flow of water to prevent the clogging of the concentrating surface by an over-accumulation 20 of gangue at any spot thereon.

A further object is to provide an improved 25 series of sluice boxes arranged in series and providing in each a concentrating surface therefor, riffles and the screen thereover, whereby a maximum of efficiency is obtained 30 in the concentration of the ore.

A further object is to provide an improved 35 means for simultaneously causing a movement of all of the riffles in the series of boxes and permitting an adjustment of the riffles, relative to the concentrated surfaces, to suit 40 conditions and give best results.

With these and other objects in view, the 45 invention consists in certain novel features of construction, and combinations and arrangements of parts, as will be more fully hereinafter described and pointed out in the 50 claims.

In the accompanying drawings—

Figure 1 is a top plan view of the improved concentrator with the upper screens broken away to illustrate parts below;

Fig. 2 is a view in side elevation;

Fig. 3 is a view in longitudinal section 45 on the line 3—3 of Fig. 1;

Fig. 4 is a view in transverse section on the line 4—4 of Fig. 3;

Fig. 5 is a view on an enlarged scale, 50 showing the riffle in elevation with its attaching coupling at one end in section, and its attaching coupling at the other end in elevation;

Fig. 6 is a fragmentary plan view, showing a riffle and portions of the two chains to which it is connected;

Fig. 7 is an inner face view of one of the riffle attaching couplings and connected chain links.

Referring to the accompanying drawings, 60 1, 2 and 3 represent sluice boxes arranged at different elevations and discharging one into the other, as is customary in the art. The boxes 1, 2 and 3 are preferably arranged at different inclines so that the speed of the 65 water is slightly different in the different boxes because of the difference in inclination. A sluice 4 directs the gangue into the first box 1, and it is carried by the force of water through the several boxes in the ordinary way.

Each of the sluice boxes 1, 2 and 3 is provided on its bottom with a concentrating 70 surface 5, the same being preferably formed by superimposed layers of coco mat 6 and carpet 7 with an anchored grating 8 on top of the mat, secured or held in any suitable manner to hold the concentrating surface in the box. Screens 9 are provided in the upper portions of the boxes to exclude the 75 larger particles of worthless material, and these screens 9 are supported on baffle plates 10 fixed to the sides of the box and serving to protect the improved riffle carrying chains 11, as will more fully hereinafter appear.

In each of the boxes 1, 2 and 3 a pair of endless sprocket chains 11 are located. These chains are adjacent the inner faces of the sides of the boxes and are mounted on 80 sprocket wheels 12 secured to shafts 13 and 14, located in the respective end portions of the boxes and projecting through the sides of the boxes. The shafts 13 and 14 are supported in bearings 15 and 16, respectively, 85 against the outer faces of the sides of the boxes, and said bearings are adjustable vertically by means of set screws 17 to vary the position of the chains vertically. The bearing 16 of the shafts 14 are also adjustable 90 longitudinally by means of set screws 18 to take up slack in the chains 13 and 14. In order that the shafts 13 and 14 may have the desired movement, the sides of the sluice boxes are made with relatively large openings 19, through which the shafts project, and covering plates 20 are held against the outer faces of the boxes to close said openings. These covering plates also serve as 95 abutments for the adjusting screws 17 and 18, and fixed brackets 21 are located on the boxes and support the screws.

The chains 11 at regular intervals are provided with coupling members 22, illustrated most clearly in Figs. 5, 6 and 7. These coupling members 22 support the riffles 23 in such a manner as to permit an angular adjustment of each rifle. 5

The inner faces of all of the couplings 22 are formed with a plurality of grooves 28 and 29, located at an angle to each other, 10 and in any of which the rifle may be held. Each coupling 22 has an extension 24, having an opening 25 therein to receive a trunnion 26 in the end of the rifle, and cotter pins or other securing devices 27 project 15 through the perforated ends of the trunnions and secure the rifle 23 in one of the grooves 28 or 29.

To permit an angular adjustment of the rifle, it is simply necessary to remove the 20 cotter pins 27 and spring the chains laterally far enough to allow the ends of the rifle to move from one groove into the other. 25

To protect the lower runs of the endless chains of the riffles, inclined baffled plates 30 are located, secured to the inner faces of the sluice boxes and projecting downwardly 30 at an incline over the lower runs of the chains 11. 35

The shafts 12 of the boxes 1, 2 and 3, are 30 provided at one end with worm gears 31 meshing with worms 32 on vertical shafts 33. These shafts 33 have suitable bearings 34, and they are all provided at their lower 35 ends with worm gears 35 meshing with worms 36 on the drive shaft 37, driven by drive pulley 38 or other suitable means. The receptacle 39 is located at the discharge end of box 3 and receives the discharge from the concentrator. 40

The operation is as follows: The gangue is discharged from sluice 4 on to the screen 9 in the upper portion of box 1, and the larger particles of worthless material are directed along the screen 9 on to the screens 45 9 of the other boxes 2 and 3, and thence into receptacle 39 without entering the lower portions of the boxes at all. Such portions of the material as can filter through the screen 9 fall downwardly upon the concentrating 50 surface in the bottom of the box and move along the same to the discharge end, and thence into boxes 2 and 3, respectively, where the same operation is carried out. In each of the boxes 1, 2 and 3, the riffles 23 55 retard the flow of water and material and can be set at different angles, as above explained, to further facilitate this function.

All of the traveling riffles are moved simultaneously by means of the gearing above 60 described, and are driven at any desired speed to give the desired results. By reason of the fact that the riffles are secured to endless chains, upper and lower runs of riffles are provided in each box which increase the 65 efficiency of the apparatus to that extent,

and also insure a thorough retardation of the precious metals and a separation therefrom of the lighter materials by reason of the fact that the upper run of riffles is moving in a direction opposite to the direction of movement of the lower run of riffles on the same pair of chains. 70

While I have illustrated and described what I believe to be a preferred form of my invention, I would have it understood 75 that various changes might be made in the general form and arrangement of the parts described without departing from the spirit and scope of the appended claims. 80

I claim:

1. A concentrator comprising a box, having a concentrating surface in the bottom thereof, endless chains in the box, couplings on the chains, riffles secured to the couplings and connecting the chains, said couplings having a plurality of grooves in their inner faces at an angle to each other for the reception of the ends of the riffles, devices securing the riffles in certain of said grooves, and means for causing the movement of the 90 said chains to move the riffles in the box. 95

2. A concentrator comprising a box, a concentrating surface in the bottom of the box, endless chains supported in the box, couplings secured to the chains and having perforated extensions thereon, baffles having trunnions at their ends positioned in the perforations of the extensions, and said couplings having a plurality of grooves in their inner faces adapted to receive the ends of 100 the riffles in any of said grooves, and means for securing the trunnions in the extensions. 105

3. A concentrator comprising a box, having a concentrating surface in its bottom, 105 shafts extending through the sides of the box adjacent its ends, sprocket wheels on the shaft in the box, a pair of endless sprocket chains connecting the sprocket wheels, said chains positioned horizontally, baffle plates 110 secured to the inner faces of the box and projecting over the upper and lower runs of the chains, riffles connecting the chains, and means for causing the turning movement of one of said shafts. 115

4. A concentrator comprising a box, having a concentrating surface in the bottom thereof, a traveling rifle in the box above the concentrating surface, inclined baffle plates secured to the inner face of the sides 120 of the box and projecting downwardly, and a screen located on the baffle plates. 125

5. A concentrator comprising a box, having a concentrating mat upon its lower face, an anchored grating located on the mat, a screen in the upper portion of the box, and a traveling rifle in the box between the screen and the anchored grating. 125
